(57) **CLAIM**

The ornamental design for an air purifier filter as shown and described.

DESCRIPTION

FIG. 1 is a front, left and top perspective view of an air purifier filter in an unfolded state, showing my new design. FIG. 2 is a rear, right and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the air purifier filter of FIG. 1 shown in a folded state.

The dashed broken lines depict portions of the air purifier filter that form no part of the claimed design.
